KITE

Francis R. Palmer, 214 S. Reymond, Las Cruces, N. Mex.

Filed June 19, 1962, Ser. No. 70,601

Term of patent 14 years

(Cl. D34—15)

FIG. 1 is a side elevational view of a kite, showing my new design;

FIG. 2 is a top plan view thereof; and

FIG. 3 is an end view of the same.

The appearance of the side opposite to that shown in FIG. 1 is substantially the same as that illustrated in said figure, with the exception that the surface ornamentation thereon is inverted.

The dominant features of my design reside in the portions shown by full lines.

I claim:

The ornamental design for a kite, as shown and described.
